Specification of Letters Patent. Patented July 5, 1921.

Application filed January 10, 1918. Serial No. 211,272.

To all whom it may concern:

Be it known that RICHARD G. INWOOD, deceased, late a citizen of the United States, and resident of South Bend, in the county of 5 St. Joseph and State of Indiana, and CHARLES H. BOMBARDIE, a citizen of the United States, and resident of Chicago, in the county of Cook and State of Illinois, have invented an Improvement in Boxes, of 10 which the following is a specification.

This invention relates to boxes and in its more specific aspect to that form of box known as a crate wherein the sides are composed of spaced slats. The purpose of the 15 invention is to provide a simple and durable box and in particular one which may be shipped in knock-down condition and readily assembled by the user without the use of special tools and without the exercise of 20 technical skill. While carrying out this purpose we at the same time provide a completed box which effects economies over previous constructions.

Our invention will be best understood by 25 the following description of one illustrative embodiment thereof taken in connection with the accompanying drawings, wherein:—

Figure 1 is a perspective view of the box with the cover fastened in place thereon; 30 Fig. 2 is a view of the parts of the shook constituting the bottom and sides and also illustrates the first step of securing one of the end sections in place according to one practicable method;

Fig. 3 is a broken away view of the end 35 of the box showing a further stage in the assembling of the end section with the bottom and sides;

Fig. 4 is a similar view showing the end 40 section in place;

Fig. 5 is a broken away view looking toward the interior corner of the box and corresponds to Fig. 4; and

Fig. 6 is a view similar to Fig. 5 showing 45 the box end completely secured in place.

Referring to Fig. 2 in the embodiment of the invention here illustrated, we provide two side sections and a bottom section, 1, 3 and 5 embodying cleats 7, 9 and 11 respectively and suitable side material 13 which may be in the form of spaced slats as shown so that the completed box will be of the kind

known as a crate. The three sections are secured together in coöperative foldable relationship by longitudinal binding wires 15 55 preferably stapled to the cleats and side material. Additional wires 17 may be used, stapled to the side material between the cleats. It will be well understood by those familiar with the art that sections 1, 3 and 5 may be folded up and the various cleats 60 will mate and, in the present instance, the tenons 19 of the cleats 9 will enter the mortises 21 of the cleats 7 and 11 and the wires will be tensioned over the dihedral angles of 65 the box. This construction will be recognized as embodying the principle of the so-called "wirebound" box.

Suitable end sections are provided, one of 70 which is clearly shown in Fig. 2. The end section 23 preferably embodies the cleat 25 corresponding to the fourth side of the box and adapted to mate with the cleats 7 and 11 of the side sections to complete the circuit 75 of the box ends in the manner illustrated in Figs. 1 and 4. The end sections also include suitable side material conveniently in the form of spaced vertical slats 27 and means is provided for securing the end sections at a location remote from the fourth side. One 80 means suitable for this purpose and illustrated in the accompanying drawings embodies a wire 29 secured to the lower ends of the slats 27, preferably at the inner side thereof, and projecting at either side beyond 85 the same.

The end section 23 may be assembled with the bottom and side sections in the manner shown in Fig. 2 by resting the slats 27 on the cleat 9 with the ends of the wire 29 extending over the shoulders or relishes 31 of the tenons 19. The side sections 1 and 5 are then partially folded up in the manner shown in Fig. 3 so that the legs of the mortises will engage the ends of the wire 29 95 bending them down as shown and tensioning them over the shoulders 31. The entire end section 23 is then swung inwardly in the direction shown in Fig. 3 to position the end in an upward position and bring the cleat 100 25 to the proper location to mate with the cleats 11 and 7. This operation will tension the wire 29 over the tenons 19 and in the structure as shown in Fig. 4 a double twist

of this wire will be provided thoroughly locking or jamming the same in the joint between the cleats. On account of this double twist we prefer to utilize mortise and 5 tenon cleats or their equivalent.

Any suitable means may be provided for holding the five faced box constructed in the manner described in proper form. We have here shown a device which acts to hold 10 the end in position and also to reinforce the same. Referring particularly to Figs. 2, 5 and 6, it will be seen that at intermediate points in the height of the end sections 23 suitable cross wires 33 are provided. These 15 wires effectually reinforce the end sections and contribute to the proper spacing of the slats 27. As shown at the top of Fig. 2, suitable staples 35 are provided in the box blank or shook in position to receive the wires 33 20 when the parts are folded up, but these staples are not driven home. Referring next to Fig. 5, it is apparent that when the end section is in the position, as shown, the wires 33 may be inserted beneath the staples 35 25 and the latter driven home with an ordinary hammer to grip the ends of the wires and so securely to hold the box end in position and also to hold the sides and ends together in box form.

30 Any suitable cover may be provided for the box. In Fig. 1 we have shown a cover 37 consisting of a number of slats connected by wires 39 and 41 adapted to mate respectively with the wires 15 and 17 of the 35 box body and having provision for detachable engagement therewith to form continuous box encircling binders. In the embodiment of the invention illustrated, we have shown the ends of these wires as formed 40 with coöperating portions of hook-and-eye fasteners to provide for their ready engagement. These fasteners are constructed by bending back the end of the wire on the standing part and intertwisting it therewith 45 to form a loop. To secure the box the end of one wire so prepared is reeved through the loop of a coöperating wire and bent down in the form of a hook. The parts are preferably so proportioned that the throat 50 of the hook is made of the intertwined wire of the end and of the standing part. This form of fastener is easily made, does not leave any raw ends of wire projecting which may tear the clothes or harm the hands and 55 may be opened and closed a number of times without the use of special tools and without impairing the strength of the wire. It will be understood, however that, while this form of fastener is desirable, we might joint the 60 wires in some other manner.

It is apparent from this description of one embodiment of our invention that we have provided a box shook which may be very conveniently shipped and stored in a knock-down condition and assembled when desired

for use without the use of special tools or the exercise of skill. It is only necessary to drive in the staples 35 with an ordinary hammer if the wires 33 and the coöperating staples are utilized. The use of wire to 70 space the slats on the end of the crate economizes wood and cheapens the construction of the box without impairing its quality as the wire has ample strength and as the end of the box is already formed by four substantial wooden cleats, to wit, cleat 25 and the three cleats 7, 9 and 11. The box without the cover is a convenient open-top receptacle for storage purposes and the cover 75 37 may be conveniently secured in position 80 and a substantial shipping container provided which has the advantages of the wire-bound type of box, that is, it is constructed of light side material and reinforcing cleats and surrounded with continuous universally 85 flexible bindings which, when a distorting strain is put upon the box, constrict about it and effectually resist distortion by their tensile strength. The result is a much stronger 90 box than those which are constructed from wood even although the latter may have metal reinforcements applied over them. As this matter is now well recognized in the art, we do not pursue the subject further in 95 this place.

Having thus described only the illustrative embodiment of our invention in considerable detail, the aspects thereof which we consider new and desire to secure by Letters Patent as our invention, we will now 100 express in the following claims:

1. A wirebound box comprising relatively foldable side and bottom sections having coöperating end cleats and connected by wire 105 bindings; end sections embraced thereby each having a cleat corresponding to the fourth side of the box adapted to interlock with the cleats of the side sections; and transverse metal reinforcing members carried by the end sections and fastening means 110 for coöperation therewith carried by the cleats of the side sections.

2. A wirebound box comprising relatively foldable side and bottom sections having coöperating end cleats and connected by wire 115 bindings; end sections embraced thereby, and coöperating metallic fastening means carried respectively by the end sections and cleats of the side sections and brought into engagement by the folding of the parts into 120 box form.

3. A wirebound box comprising relatively foldable side and bottom sections having coöperating end cleats and connected by wire 125 bindings; end sections embraced thereby; and transverse metal reinforcing members secured to the outer sides of the end sections and adapted to be fastened to the inner faces of the cleats of the side sections.

4. A wirebound box comprising relatively 130

foldable side and bottom sections having co-operating end cleats and connected by wire bindings, and end sections having cleats for the fourth side of the box interlocked with the cleats of the side sections, said end sections comprising spaced vertical slats secured to said fourth cleats and transverse wires on which said slats are secured, the end sections being connected with the cleats of the side sections below the fourth side wholly by said wires.

5. A wirebound box comprising relatively foldable side and bottom sections having co-operating end cleats, and end sections 10 braced thereby having a wire secured across the bottom provided with free ends adapted to be gripped between cleat ends at the bottom corners of the box and to be secured wholly by such gripping of the cleats to hold 15 the end section in place.

6. A box comprising side and bottom sections having mating interlocking cleats secured together in co-operative foldable relationship by binding wires, and end sections 20 each carrying a transverse wire having projecting ends interlocked with the respective joints between the bottom cleat and side cleats to hold the end section in place.

7. A box comprising side and bottom sections 25 having mating cleats interlocked by mortise and tenon joints and secured together in co-operative foldable relationship by binding wires, end sections each carrying a transverse wire having ends projecting 30 into the joint between the cleats and tensioned over the tenon and its shoulder by the mortise.

8. A box shook comprising side and bottom sections each comprising side material 35 and cleats and connected in co-operative foldable relationship by binding wires, end sections comprising a plurality of slats secured on transverse wires and means carried by the cleats of the side sections for fastening 45 said wires thereto to flexibly secure the end sections in place when the shook is folded into box form.

9. A box shook comprising side and bottom sections each comprising side material 50 and cleats and connected in co-operative foldable relationship by binding wires, end sections comprising a plurality of slats secured on transverse wires and means carried by the cleats of the side sections for fastening 55 said wires thereto to flexibly secure the end sections in place, said end sections including also a cleat corresponding to the fourth side of the box and co-operating with the cleats of said side sections.

60 10. A box comprising, in combination, three separate sections of side material having interlocking cleats and connected in foldable relationship by binding wires, and end sections each having a cleat across the 65 top corresponding to the fourth side of the

box adapted to interlock with the cleats of the side sections and having a wire secured across the bottom provided with free ends adapted to be gripped and tensioned by the cleat joints at the corners opposite from said top cleat.

11. A box comprising side and bottom sections, each comprising side material and cleats and connected in co-operative foldable relationship by binding wires, and end sections each having a transverse cleat at the top adapted to engage and interlock with the cleats of the side sections and a transverse wire at the bottom adapted to be engaged and tensioned by the cleats of the side 75 and bottom sections.

12. A box comprising side and bottom sections having interlocking cleats secured together in co-operative foldable relationship by binding wires, and end sections each carrying a transverse wire having projecting ends interlocking with the joints between the cleats, whereby said wire is tensioned to hold the end securely in position.

13. A wirebound box comprising relatively foldable side and bottom sections having co-operating end cleats, and an end section 85 embraced thereby having a wire secured thereto provided with free ends adapted to be gripped between the side and bottom sections of the box and to be secured by such gripping to hold the end section in place.

14. A wirebound box comprising relatively foldable side and bottom sections having co-operating end cleats and an end 90 embraced thereby having a transverse wire secured thereto provided with projecting ends adapted to be gripped between sections and secured by such gripping to hold the end in 95 place.

15. A wirebound box comprising a plurality of relatively foldable sections having co-operating end cleats and a removable section 100 embraced thereby having a transverse wire secured thereto provided with free ends adapted to be engaged by joints between said foldable sections and to be secured by such engagement to hold the removable section in place.

16. A wirebound box comprising a plurality of relatively foldable sections having co-operating end cleats and a removable section 110 embraced thereby having a transverse wire secured thereto provided with free ends adapted respectively to engage opposite foldable sections to hold the removable section in place.

17. The combination of a box blank having a plurality of sections of side material 125 and cleats connected together in co-operative foldable relationship with binding wire, and a removable section having a transverse wire secured thereto provided with free ends adapted to be gripped by joints between sec- 130

tions of the blank when the blank is foldable into box form.

18. A box comprising side and bottom sections having mating interlocking cleats secured together in co-operative foldable relationship by binding wire and an end section carrying a transverse wire having projecting ends interlocking with the respective

joints between the bottom and side sections to hold the end section in place.

In testimony whereof, we have signed our names to this specification.

MARY CAIN INWOOD,
Administratrix of Richard G. Inwood, deceased.

CHARLES H. BOMBARDIE.
